UNITED STATES PATENT OFFICE.

HANS CHRISTENSEN, OF FORT ATKINSON, WISCONSIN.

MOP-WRINGER.

1,177,681.

Specification of Letters Patent.

Patented Apr. 4, 1916.

Application filed August 11, 1915. Serial No. 44,867.

To all whom it may concern:

Be it known that I, HANS CHRISTENSEN, a citizen of the United States, residing at Fort Atkinson, in the county of Jefferson and State of Wisconsin, have invented certain new and useful Improvements in Mop-Wringers, of which the following is a specification.

My invention relates to improvements in 10 mop wringers, and more particularly to that class or type in which a mop receiver or receptacle is removably mounted within and detachably secured to the edge of the scrub pail or bucket and into which the mop is 15 designed to be inserted and then twisted so as to squeeze the water therefrom such water being adapted to return into the mop pail or bucket.

The primary object of my invention is to 20 provide a generally improved article or device of this class of exceedingly simple, cheap, and efficient construction better adapted to the purposes for which it is designed than any other device of the same 25 class with which I am acquainted.

More specifically stated, this invention has for its object the provision of a mop receiver or receptacle of improved form which does not require any considerable downward pressure in order to cause the necessary connection between the mop head or rag and the receiver, so that upon the mere twisting or rotation of the handle of the inserted mop the latter will be properly 35 wrung or squeezed in the operation of squeezing or expressing the water therefrom and returning the same to the mop pail or bucket.

A still further object is the provision of 40 an improved mop receiving and engaging bottom for such mop receiver or receptacle, said bottom comprising a longitudinally corrugated conical shaped member terminating about its base or outer periphery in 45 a series of drain openings which latter also act to initially receive and engage with the free edges of the mop cloth or rag when the latter is initially inserted preparatory to the initial twisting of the same in the 50 squeezing operation.

With the above mentioned and other ends in view, the invention consists in the novel construction, arrangement, and combination of parts, hereinafter described, illustrated

in one of its embodiments in the accompanying drawings, and particularly pointed out in the appended claims.

Referring to the drawings forming a part of this specification, Figure 1, is a top plan view of the improved mop wringer or receiver detachably mounted within and secured to the edge of an ordinary mop pail or bucket preparatory for use. Fig. 2, a side elevation of the same from the pail engaging and supporting side thereof, the 65 wringer or receiver being removed from the pail for the purpose of clearer illustration of the parts. Fig. 3, a central vertical sectional view taken through the pail engaging and supporting side thereof. 70

Similar numerals of reference designate like parts throughout all the figures of the drawings.

The improved mop wringer comprises a suitable mop receiver or receptacle 1, preferably tapered and flaring as shown, said receiver or receptacle being provided with a plurality of regularly spaced longitudinally extending corrugations 1^a, the latter being preferably formed of plane sides arranged at an angle to each other and converging toward the base or bottom portion of the receptacle as shown. 75

As a means of properly receiving and gripping the free or loose ends of the mop rag or cloth, the mop receiver or receptacle 1, is provided with a conical shaped mop engaging bottom 2, the latter being provided with a series of longitudinally extending similarly shaped corrugations 2^a, 80 said corrugations converging at the apex portion of the cone shaped bottom, the apex or crown portion of the substantially V-shaped corrugations 2^a, however, meeting and being secured to the lower edges or 95 parts of the apex or crown portions of the corrugations 1^a, of the receiver or receptacle 1, to form angular shaped drain openings 3, as shown most clearly in Fig. 1 of the drawings, said drain openings being also 100 admirably adapted to receive and engage with the free or loose ends of the mop rag or cloth in the initial twisting or squeezing movement of the same through the rotation of the mop handle in the wringing operation. 105

The apex or crown portions of the corrugations 1^a, and 2^a, may be connected to

each other at the base of the receptacle and conical bottom in a suitable and convenient manner, as for example,—by soldering, welding, or the like, and it will be seen that such drain openings 3, also form mop engaging portions as likewise the corrugations 1^a, and 2^a, the conical bottom 2, being adapted to spread out the free or depending edges of the mop rag or cloth when inserted in the improved receiver or receptacle, the spread out portions of the mop cloth or rag being directed into the annular space formed by the downwardly converging space intermediate the downwardly converging walls of the receptacle and bottom. The mop rag or cloth may be readily disengaged by twisting the same which will act to detach it from the corrugations and mop engaging drain openings 3.

As a convenient means of removably mounting the mop receiver or receptacle 1, within the scrub pail or bucket 4, and detachably mounting and supporting the same upon one edge of the pail or bucket, one side of the mop receiver or receptacle 1, is provided with a supporting plate or bracket 5, (see Fig. 2) said supporting plate or bracket 5, terminating at its top in a pair of supporting hooks 5^a, adapted to receive and take over the upper edge of the pail or bucket 4, and securely maintain the mop receiver or receptacle 1, in proper position as indicated in Fig. 1 of the drawings while in use.

From the foregoing description, taken in connection with the accompanying draw-

ings, the operation and advantages of my invention will be readily understood.

Having thus described one of the embodiments of my invention, what I claim and desire to secure by Letters Patent, is,—

1. A mop wringer, comprising a tapered corrugated receptacle terminating in a corrugated conical bottom having annularly arranged drain openings. 45

2. A mop wringer, comprising an inverted truncated cone-shaped receptacle terminating in a conical shaped bottom, said receptacle and bottom having longitudinally extending intersecting corrugations terminating in drain openings at the base portion thereof. 50

3. A mop wringer, comprising a longitudinally corrugated receptacle having a similarly corrugated conical shaped mop engaging bottom forming annularly arranged drain openings at the base of said bottom and receptacle. 55

4. A mop wringer, comprising a longitudinally corrugated flaring receptacle, and a longitudinally corrugated conical bottom, the apex or crown portions of said corrugations being connected to each other at the base of said receptacle and conical bottom providing mop engaging drain openings. 60

In testimony whereof I have affixed my signature in the presence of two witnesses.

HANS CHRISTENSEN.
